Attorney,

UNITED STATES PATENT OFFICE.

THOMAS W. MORAN, OF LOUISVILLE, KENTUCKY.

BARREL-FILLER.

SPECIFICATION forming part of Letters Patent No. 392,448, dated November 6, 1888.

Application filed July 28, 1888. Serial No. 281,322. (No model.)

To all whom it may concern:

Be it known that I, THOMAS W. MORAN, a citizen of the United States, and a resident of Louisville, in the county of Jefferson and State of Kentucky, have invented certain new and useful Improvements in Barrel-Fillers; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of a plan view of my improved barrel-filler. Fig. 2 is a horizontal section of same. Fig. 3 is a vertical section. Fig. 4 is a detail view of plug.

The invention relates to improvements in barrel-fillers; and it consists in the construction and novel combination of parts, as hereinafter set forth.

The present invention consists more particularly in improvements in the filler for which Letters Patent were granted to me under date of April 2, 1878, and numbered 201,887.

In the device patented as above, objection is found in the fact that when the barrel is full and the cut-off valve automatically closed a quantity of oil or other liquid is retained in the pipe between the valve and the liquid in the barrel, and when the filler is removed from the bung of the barrel the air, rushing into the filler, causes the said oil or other liquid to discharge upon the floor or upon the outside of the barrel. To obviate this difficulty in the present case I provide an air-inlet that admits air in the rear of the oil at the proper time and causes the oil to discharge into the barrel, as will hereinafter more fully appear. I have further improved the filler by rendering the main trigger adjustable, so that the releasing thereof may be regulated to the pressure of the liquid upon the float.

The improvement further consists in dispensing with the T-coupling and extending the valve-casing in lieu thereof, and also by discarding one of the stuffing-boxes, thus materially reducing the cost of the filler.

Referring by letter to the drawings, A designates the valve-casing, closed at one end,

preferably by the handle *a*, and engaging at its opposite internally-threaded end with the main tube *B*.

C represents the valve-plug, having a transverse opening, *a'*, within the casing, and provided at one end with the angular stem *b*, projecting outwardly, and the journal or lug *b'* at its opposite end. The valve or plug seat *D* is threaded at one end and provided with the bearing-head *E*, which engages a stuffing-box, *F*. The plug *C* has a small longitudinal open way, *G*, which communicates at one end with the interior of the casing, as shown at *c*, and the opening *c'* at its other end registers at a certain time with the opening *d* through the wall of the valve-seat.

G' is a double-arm lever having one of its arms at the end provided with an angular opening to engage the angular plug-stem *b*, and its opposite arm is provided with a round opening to engage the journal *b'*. A bail, *H*, has its outwardly-turned ends inserted in openings in the arms of the lever *G*, as shown, and a spiral spring, *f*, extends from the bail to a connection with the collar *f'*, which is adjustable on the tube *B*, a set-screw, *g*, being provided to secure the collar in any desired position to regulate the spring-tension.

I is a tube depending from the threaded opening *h* in the valve-casing, designed to be inserted through the bung-hole of the barrel, and through which the liquid passes into the barrel. A tube, *J*, extends upwardly from the conical bottom within the tube *I*, and a smaller tube, *i*, has an outward opening from the top of the tube *J* through the upper wall of the valve-casing. A suitable float, *k*, is loosely placed within the tube *J*, and a wire, *j*, extending therefrom through the tube *i*, engages the long arm of the trigger *L*, which has its head pivoted within the lugs *l*.

M is a trigger for engaging the double-arm lever, pivoted near its end within the lugs *l* and sufficiently long to engage the hook of the trigger *L*. The lugs *l* are secured to the handle *a* by the bolt *l'*, which passes through a longitudinal slot, *m*, in said handle, and the nut *n*. The object of the slot-opening is to provide for the horizontal adjustment of the trigger *L*, which is desirable should the hooks of the triggers become worn and require filing.

A spider-leg collar, *o*, on the tube *I* is adapted to move up and down thereon, and the legs, resting on the outer surface of the barrel, allow the escape of air from the barrel.

5 P is a universal-coupling joint adapted to connect the filler with the large oil-tank; but as this coupling has heretofore been patented by me I do not claim it, broadly, herein.

In operation the filler is connected with the tank by means of the coupling-joint and the tube *I* is inserted through the bung-hole of the barrel. The double-arm lever is then thrown forward to an engagement with the trigger *M*, which at the same time engages the trigger *L*. The filler is now in operation to fill the barrel. When the liquid reaches to the top, or nearly so, of the barrel, it forces the float upwardly, releasing the double-arm lever, which is reversed or drawn in the opposite direction by 15 the coiled spring, thus closing the valve and placing the opening *G* in communication with the outward opening, *d*, allowing the entrance of air, which forces all of the liquid out of the valve-casing into the barrel.

Having described my invention, what I claim 25 is—

In a barrel-filler, the combination of the valve-casing having the opening *d*, the handle provided with the slot, the plug having the inwardly and outwardly opening way *G*, the head *E*, the stuffing-box *F*, the double-arm lever having the angular opening and the round opening, respectively, in its arms, the bail engaging said arms, the coil-spring engaging the bail, and the adjustable collar, the trigger *L*, 30 the trigger *M*, pivoted in the adjustable lugs, the float, the tubes *I* and *J*, the tube *B*, and the universal-coupling joint, substantially as specified.

In testimony whereof I affix my signature in 35 presence of two witnesses.

THOS. W. MORAN.
